UNITED STATES PATENT OFFICE.

JOHN DARBY, OF SUMMIT, NEW JERSEY.

LAMP-SOCKET.

1,119,928.

Specification of Letters Patent.

Patented Dec. 8, 1914.

Application filed March 12, 1910. Serial No. 548,831.

To all whom it may concern:

Be it known that I, JOHN DARBY, a citizen of the United States, residing in Summit, in the county of Union and State of New Jersey, have invented new and useful Improvements in Lamp-Sockets, of which the following is a specification.

The invention relates to electric lamp sockets and more especially in certain features to sockets having a double pole and double break to control the current, althought in certain of its features the invention is applicable to other kinds of sockets.

The objects of the invention are in part set forth hereinafter and will in part be obvious to those skilled in the art.

The invention consists in the novel parts, articles, arrangements, constructions, combinations and improvements herein shown and described.

The accompanying drawings, referred to herein and forming a part hereof, illustrate one embodiment of the invention, the same serving in connection with the description herein to explain the principles of the invention.

Of the drawings: Figure 1 is an elevation of a lamp socket, with one socket head in section, constructed in accordance with the principles of the invention, and substantially on the line A—B of Fig. 2 looking in the direction of the arrows; Fig. 2 is a central section through Fig. 1 perpendicular to the plane of the paper, and looking to the right, but with the controller and contacting parts shown in elevation; Fig. 3 is a top plan of the controller, its actuating means and associated part, and corresponds substantially to a top plan of Fig. 1 with the upper socket head and its binding posts removed; Fig. 4 is a sectional plan on the line C—D of Fig. 1 and shows the detent piece and detent spring in detail; Fig. 5 is an enlarged perspective of the supporting standards, the controller support and the controller actuating means; Fig. 6 shows a top plan and an elevation of the controller; Fig. 7 is a top plan of the controller showing the brushes; Fig. 8 is a perspective drawing of one of the brushes; Fig. 9 is an elevation of the socket head showing the manner of mounting the binding posts, and the protecting ears for wire connections; and Fig. 10 is an elevation of socket head looking at

Fig. 9 from the right—showing channel for chain protection and recess for removal of funnel.

Referring to the accompanying drawings, which illustrate by way of example, one embodiment of the invention, a head 1 is shown and also a head 2 with a suitable supporting connection therebetween. According to one feature of the invention the said supporting and connecting structure is in one piece comprising the standards 3 and 4 and the cross member 5 shown provided with the screw holes 6 and 7 which serve to fasten it to the head 1 by screws 8 and 9 or other suitable fastening devices. The head 1 may be channeled to receive the part 5, as shown in Fig. 2 of the drawings. The standards 3 and 4 are shown provided at their other ends with transverse portions 10 and 11 provided with suitable apertures into which the screws 12 and 13 are threaded to connect the standards 75 to the head 2.

The socket provides a double pole, double break current control; that is, each branch of the circuit is broken and made at two points separated from each other. A contact piece 20 of angled form is shown resting in the channel 21 in the socket head 1 and connecting electrically by means of the screw 22 with the screw shell 23 which receives the lamp base. A similar angled contact piece 24 is shown at the opposite side of the socket 1 and this also may rest in the channel 25 in the socket head 1. The contact piece 24 connects electrically by means of the screw 26 with the center contact 27 which connects to the central lamp terminal. Two opposing contact pieces are provided, the contact piece 30 likewise shown of angled form extending toward and in alignment with the contact 20. The portion 31 is shown bent at right angles and is supported in the head 2 by the screw 32. Said contact piece serves also as a binding post, the binding screw 33 being threaded thereinto to hold and make contact with the line terminal 34. The head 2 is shown grooved or recessed at 35 and as having extending ears 36 and 37 on either side of the binding post 30. This permits the line wire to be brought down and held within the socket structure, and to be protected thereby. The contact piece 40 is likewise shown opposite and extending toward the contact piece 24

on the opposite side of the socket. The angled part 41 is shown held to the head 2 by the screw 42. The line wire terminal 45 is shown passing down through the groove 44 and fastened to the member 40 by the binding screw 46, corresponding ears or projections being provided, the ear 47 being shown in Fig. 2 of the drawings.

A controller is shown mounted substantially centrally of the socket and with its axis arranged parallel or concentric with the socket axis. The controller is shown consisting of a disk 50 of insulating material having a four toothed ratchet 51 and a four faced detent part 52 integral therewith. The controller is shown rotatably mounted on the stud shaft 53 carried in the aperture 54 in the part 5 of the connecting structure and having its head 55 carried in a recess in the socket head 1, thus giving a firm and steady mounting for the stud shaft. The shaft 53 is shown projecting into but not through the controller. The lower face of the detent piece is shown resting upon the upper face of the part 5 and rotating thereon, Figs. 1 and 2. A suitable detent member, such as a spring 56, is shown coacting with the detent piece 52.

Brushes 60 and 61 are provided upon the controller 50, these brushes being shown with two contact faces 62 and 63 which are separated so as to have an independent spring action, one coacting with one contact piece and the other with the opposed contact piece. This will give a firm clean contact with each of the contact pieces whether they be exactly in alignment or not. The contact pieces are shown with body portions 64 and 65, respectively, terminating in an angled part 66 and 67 which fits into the kerfs 68 and 69 in the controller 50. The parts 66 and 67 are also provided at either side with ears 70 which may be bent down into recesses 71 upon the controller body to firmly hold the brushes in position. The brushes are thus inexpensively made, and easily, rapidly and economically assembled with the controller and are firmly and accurately held in position. The actuating means for the controller is, in the present embodiment, likewise supported from the connecting structure for the socket head, and also provides for a direct and straight line pull for the chain. As embodied herein a support and guide 75 is shown supported upon the standards 3 and 4 and carrying a pawl piece 76 shown of generally flat form and with the projections 77 and 78 bent up therefrom and having apertures 79 and 80 through which the support and guide 75 passes loosely. The pawl piece 76 is provided with a pawl tooth 81 at one side thereof, and is acted on by a suitable spring to return it to initial position after it has been actuated.

In Figs. 1 and 2 a spring 84 is shown carried about the support 75 several torsional twists being made in the spring and one of its extending ends being hooked in a recess of the ear 77 of pawl piece 76, and the other end hooked in a recess of standard 3. Thus the torsional strain in the spring will serve to throw the pawl 81 into engagement with the ratchet and allow it to yieldingly slip over the ratchet on the return movement of the pawl piece. In the embodied form also the actuator travels and is guided along a path substantially across the axis of the controller. In Fig. 5 a spring 85 is shown engaging the pawl piece 76 at the opposite side from the pawl tooth 81, the other end of said spring being attached to the standard 4. Either arrangement of the spring throws the pawl tooth positively down upon the face of the ratchet 51 so as to insure the actuation of the controller under the pull of the chain and still allows it to yield easily upon the return movement.

The chain funnel 90 is shown mounted in a slot 91 at the angle joining the standard 3 and the bent part 10 thereof, the part 10 having an enlarged slot 92 therein. The inner end of the funnel 90 is enlarged or flared so as to slip into the enlarged part 95 only and thus to hold the funnel 90 from being pulled outwardly, while the socket head 2 is shown recessed at 100 to allow the ready removal of the funnel—after assembling, the outer shell casing prevents vertical movement. The projection 77 is shown slotted at 93 to support the chain 94, and the projection 78 is shown slotted and curved at 95 (see Figs. 1 and 5) to firmly hold the end of the chain. In Fig. 10 portions 101 and 102 of the socket head 2 are shown projecting on either side of the chain (see Figs. 1, 2 and 10), whereby the chain is prevented, should it ever be run up slack, from dropping down and possibly short circuiting the socket. In said figure the chain 94 and guide 75 are shown in outline in order to make clear the relation of the parts just described.

By the present invention a socket is provided which is of exceedingly few parts, which are strongly constructed, which are easily assembled, and which are positive and simple in their operation, and in which a direct chain pull is provided for the actuating means, and wherein the gapage available is extraordinarily large, while at the same time the entire socket is very small and compact, thus making the socket safe for extraordinary heavy currents. A strong and quick spring action with a wiping contact and a sudden break is also provided by the arrangement of the brushes and the detent.

The invention is not limited to the exact

construction shown, but variations may be made in the construction within the scope of the accompanying claims.

What I do claim and desire to secure by Letters Patent, is:

5. 1. A lamp socket including in combination a rotatable controller, a ratchet integral therewith, a guide arranged in a straight line, at right angles to the axis of the controller and past the face of the ratchet wheel, a pawl traveling along said guide, and connections for moving the pawl.
10. 2. A lamp socket including in combination a stub shaft, a controller rotatably mounted thereon, and a ratchet on the end of the controller, and a guide extending past the end of the controller and a pawl traveling along said guide and the free end of said shaft engaging said ratchet.
15. 3. A lamp socket including in combination a stub shaft, a controller rotatably mounted thereon, and a ratchet on the end of the controller, and a guide extending in a right line past the end of the controller and a pawl traveling along said guide and the free end of said shaft engaging said ratchet.
20. 4. A lamp socket including in combination opposed socket heads, a controller, shorter than the distance between said heads, rotatably mounted upon one of said heads only, thereby leaving a free space between the controller and the other head, a guide arranged in said free space and actuating means for said controller traveling on said guide in said free space.
25. 5. A lamp socket including in combination opposed socket heads, a controller, shorter than the distance between said heads, rotatably mounted upon one of said heads only, thereby leaving a free space between the controller and the other head, a guide arranged in said free space, a ratchet on the free end of said controller, and a pawl traveling on said guide across the socket in said free space, the pawl engaging the ratchet.
30. 6. A lamp socket including in combination two opposed heads, supporting connections therebetween, a controller rotatably supported from one of said heads only, leaving a free space between the end of the controller and the other head, a guide supported between said supporting connections in said free space and actuating means for the controller traveling along said guide.
35. 7. A lamp socket including in combination two opposed heads, supporting connections therebetween, a controller rotatably supported from one of said heads only, leaving a free space between the end of the controller and the other head, a guide supported between said supporting connections in said free space, a pawl member sliding along said guide, and a ratchet fixed to the free end of the controller and engaged by said pawl.
40. 8. A lamp socket including in combination, a cylindrical lamp socket, a cylindrical controller mounted concentrically within the socket, a pair of contacts at one side of said socket, said contacts being in one branch of the circuit, and one connecting to the line and the other to the lamp, a pair of contacts on the opposite side of the socket and also of the controller, said pair of contacts being in the other branch of the circuit, and one of them connecting to the line and the other to the lamp, two brushes mounted on the periphery of said controller, each brush connecting the two contacts of a pair at alternate actuations of the controller.
45. 9. A lamp socket including in combination the socket heads, and a support between the socket heads extending diametrically thereof, a controller mounted on the stub shaft, an actuator for said controller, and a guide upon which said actuator travels, said guide being mounted transversely of the socket upon said support.
50. 10. A lamp socket including in combination the socket heads, two standards connecting said heads at points substantially a diameter apart, a guide supported across the socket on said standards, a pawl piece moving on said guide, a controller and a ratchet therefor engaged by said pawl.
55. 11. A lamp socket including in combination two socket heads, two standards connecting said heads at points substantially a diameter apart, a controller rotatably supported from one of said heads only, leaving a free space between the end of the controller and the other head, a guide arranged across the socket and having its ends supported in said standards, a pawl piece moving along said guide, a ratchet at the end of said controller and engaged by said pawl.
60. 12. A lamp socket including in combination two opposed heads, a single strip bent into three right angled parts, means for fastening the central part to one of said heads and the ends of the strip to the other of said heads, and a guide for a controller supported between the opposite standards formed by said strips, a controller and a controller actuator traveling on said guide.
65. 13. A lamp socket including in combination two opposed heads, a single strip formed to provide two standards substantially diametrically opposite each other, said strip being fastened to both of said heads, a support carried by said strip and a controller rotatably mounted thereon.
70. 14. A lamp socket including in combination two opposed heads, a single strip formed to provide two standards substantially diametrically opposite each other, said strip being fastened to both of said heads, a support carried by said strip, a controller 75
75. 80. 85. 90. 95. 100. 105. 110. 115. 120. 125. 130. 135.

rotatably mounted thereon, and actuating means for the controller carried on said strip.

15. A lamp socket including in combination two opposed heads, a single strip formed to provide two standards substantially diametrically opposite each other, said strip being fastened to both of said heads, a support carried by said strip, a controller 5 rotatably mounted thereon, a guide mounted on said strip and a controller actuator traveling on said guide.

16. In a lamp socket, a guide, a pawl carrying member slidable along said guide, and 15 capable of a slight rocking motion relatively to the guide, a ratchet adjacent to said guide and pawl piece, and means for rocking said member during its sliding motion along the guide whereby the pawl is thrown into engagement with the ratchet.

17. In a lamp socket, a guide, a pawl adapted to slide along and to rock about said guide, and means tending to slide the pawl along the guide and to rock it about 25 the guide.

18. In a lamp socket, a guide, a pawl adapted to slide along and to rock about said guide, means tending to slide the pawl along the guide and to rock it about the 30 guide, and a rotating ratchet coöoperating with said pawl.

19. A lamp socket including in combination a cylindrical socket, a rotatable cylindrical controller substantially concentric 35 with the socket, two contacts at one side of the socket, two contacts on the opposite side of the socket, a brush carried on the side of the controller to connect the contacts on one side and a brush on the opposite side of 40 the controller to connect the two opposite contacts.

20. In a lamp socket a straight guide, a member slidable along said guide and having a slight transverse rocking movement 45 relatively to the guide, a chain for pulling said member in the direction of the guide, a pawl carried by said member at one side from the guide, a spring acting on said guide against the pull of the chain, and a 50 ratchet for the pawl.

21. In a lamp socket a controller of insulating material, a plurality of recesses therein, and a metal brush projecting from said controller, and bent into said recesses to 55 hold the brush in place on the controller.

22. A lamp socket including in combina-

tion two opposed heads, a controller, a guide, an actuator for the controller moving along said guide, a pull chain connected to the actuator, and projections on the socket 60 head at each side of the chain which co-operate with said guide to prevent the chain dropping on the controller.

23. In a lamp socket, two socket heads, a standard connecting said heads, an angled 65 portion in said standard, a slot at said angle having a narrow portion in said standard and a wide portion in said angled part, and a chain funnel having a groove therein fitting in the narrow portion of the slot 70 and an enlarged part fitting and passing through the wide portion of the slot.

24. In a lamp socket, a controller, a ratchet, a guide, a pawl loosely mounted upon and sliding along said guide, and a 75 spring acting both to press the pawl along the guide and to turn it down into engagement with the ratchet.

25. A lamp socket including in combination a guide, a pawl carrying member slid- 80 able along said guide and capable of a slight rocking motion about said guide, means for sliding said pawl carrying member along said guide, and a spring acting against said sliding movement and also tending to rock 85 said pawl about said guide, and a ratchet for said pawl.

26. A lamp socket including in combination a cylindrical controller, having a ratchet at one end thereof, a guide adjacent to said 90 end, a pawl carrying member slidable along and rockable about said guide, a spring tending to slide and rock said pawl carrying member, and hand actuated means for sliding said pawl carrying member, 95 against said spring.

27. A lamp socket including in combination a cylindrical controller having a ratchet at one end thereof, a guide adjacent to said end, a pawl carrying member slidable along 100 and rockable about said guide, a spring tending to slide and rock about said pawl carrying member, and a chain connected to said pawl carrying member and extending outside the socket.

In testimony whereof, I have signed my name to this specification, in the presence of two subscribing witnesses.

JOHN DARBY.
